MEDALLION

Adolph Frankenthaler, 10 W. 33rd St., New York, N.Y.

Filed Dec. 12, 1962, Ser. No. 72,819

Term of patent 14 years

(Cl. D29—19)

FIG. 2 is a rear view thereof; and

FIG. 3 is a sectional view taken on the line 3—3 of FIG. 1.

The dominant features of my design reside in the full line showing on the medallion disclosed of the specific border combined with the figure and scroll all as shown.

I claim:

The ornamental design for a medallion, substantially as shown and described.
